ALADÁR DOMAN, OF BUDAPEST, HUNGARY, ASSIGNOR TO LAMPEN-UND METALL-WARENFARIKEN R. DITMAR-GEBRUDER, BRUNNER A. G., OF VIENNA, AUSTRIA, A FIRM.

BURNER FOR LIQUID FUELS.

Application filed May 17, 1927, Serial No. 192,108, and in Hungary May 22, 1926.

The appliances hitherto known for the combustion of liquid fuels for lighting or heating purposes exhibit various disadvantages.

5 Above all, the fuel is not burnt completely, so that its lighting or heating power can only be incompletely utilized. The luminous flame is not sufficiently white, and in the case of heating the flame cannot evolve the 10 desired degree of heat because the supply of air to the flame cannot be regulated independently of the adjustment for the most favourable evolution of gas and height of flame. The flame therefore does not receive sufficient 15 air, combustion does not take place without smoke, and the air of the room to be lighted or heated is rendered foul.

The fuel container becomes highly heated when the flame is burning, which has the result 20 that the volatile and foul smelling constituents of the liquid fuel escape and evaporate.

The wick necessary for the formation of the flame requires cleaning or trimming each 25 time the apparatus is used, and also renders frequent changing necessary, without however enabling uniformity of the flame to be attained notwithstanding the cleaning. After the extinction of the flame, foul smelling 30 gases are evolved therefrom for some time longer.

Now attempts have frequently been made to eliminate all these objections and disadvantages which arise when liquid fuels such 35 as petroleum and the like are employed. The appliances suggested for this purpose and also actually employed in various forms are however very complicated, require constant attention, and for the supervision thereof 40 special technical knowledge and skill are mostly necessary. Moreover the cost of manufacture is considerable, and nevertheless failure is to be expected in a comparatively short time.

45 The apparatus forming the subject-matter of the present invention eliminates the above-mentioned disadvantages and involves no alteration in the construction of the lamps at present in use, since it can be fitted into existing petroleum lamps without any alteration.

50 The essence of the invention resides in the fact that the strength of the light or the capacity for the evolution of heat is main-

tained constant in one and the same burner independently of the shifting of the wick, 55 that is to say, the flame does not become smoky when the wick is turned up, irrespectively of whether it is a lighting or a heating flame. This result is mainly produced owing to the fact that that part of the wick which serves for the formation of the flame whether the flame burns in contact with it or the wick by contact with a metallic part 60 of the apparatus, only effects the gasification of the fuel, is limited downwards to a certain line. Underneath this boundary line the wick remains cool, and does not burn. Also the flame cannot strike back to this lower part of the wick even if gases should be evolved at that point.

70 Now as the flame is not evolved directly at the end of the fuel container, but is divided from the latter by a portion of the wick which remains cold, the container also remains cold. The premature gasification of the volatile 75 constituents of the liquid fuel, with all its unpleasant accompanying phenomena, therefore does not occur. The dividing of the wick into a hot zone and a cold zone, or the limiting of the flame in a downward direction is brought about by a fixing or disc having the shape of the upper margin of the wick, said fixing plate being solid or formed with holes in its upper surface or connected with a perforated or gauze ring at which 80 alone the flame burns during the normal operation of the lamp, and means for guiding air along the part of the wick located below said fixing plate and projecting out of the wick tube for the purpose of cooling the said part 85 of the wick. The flame receives in this way great steadiness, which renders it suitable 90 for an incandescent light burning without pressure.

95 The lighting or heating power may be utilized to their maximum, and the candle power and evolution of heat in one and the same lamp remain independent of the adjustment and constant, and the fuel can be completely consumed, the regulating of the evolution of gas, as contrasted with known appliances, being made independent of the quantity of air applied internally to the burner. The quantity of air supplied on the outside, the direction of its flow, and the angle at which the air meets the flame, can be 100 105

varied, without the most favourable height of the flame, which is dependent upon the dimensions of the appliance, the air pressure prevailing in the room, and the temperature 5 in the room having to be altered.

The flame does not smoke. A round flame can be formed above a flat wick, and similarly a flat flame above a round wick, that is to say, the form and dimensions of the flame 10 can be varied according to varying requirements.

Upon the flame being extinguished the gas burns without smell and without leaving any residue.

15 If the flame is to be employed for the production of incandescent light, an incandescent mantle of close mesh and comparatively great strength is placed in the lamp and brought to incandescence, in such a manner 20 that the same is surrounded closely by a ring of flame, which, however, need not penetrate the fabric of the incandescent mantle. The improved effect thereby produced expresses itself in a brighter flame, which is 25 more agreeable to the eye. In the event of the incandescent mantle being accidentally damaged the lamp can immediately be utilized as an ordinary wick-burner lamp.

30 The burner works without preheating by simply igniting the flame thereon.

In the accompanying drawings several constructional examples of the appliance forming the subject-matter of the present invention are illustrated:—

35 Figure 1 shows in partial sectional elevation a round-burner petroleum lamp with internal and external air regulation.

40 Fig. 2 shows vertical section through the upper part of a round wick burner with another form of fixing plate and with an air sleeve.

Figs. 3 and 4 show a plan and a vertical middle section of a flat burner with a fixing plate.

45 Figs. 5 and 6 show in plan and vertical middle section another form of fixing plate for the conversion of the flame of a flat burner into a round flame.

50 Figs. 7 and 8 illustrate in plan and in vertical middle section a modified form of the fixing plate in combination with an exchangeable air sleeve.

55 In Figure 1, 1 denotes the fuel container of a petroleum lamp. A tube 5 passing through the container 1 and supported by a bow 5^x leads the air that enters through apertures 8 in the foot of the lamp to the internal surface of the flame, which is formed at the end of the wick, and which is deflected and spread 60 out by a support 7, mounted at the upper end of a rod 9, which is centrally held and guided in brackets 10 and 11 within the tube 5. For the raising and lowering of the rod 9 there is provided a transverse pin 12 guided in an 65 ascending arcuate slot 14 in the upper part

of the foot of the lamp, and provided with a handle 13, the said transverse pin 12 being secured in the rod 9. By moving the handle, the distance of the support 7 from the ring of flame, and the quantity of air supplied 70 through the tube 5, as well as its velocity, can be altered within very narrow limits. The lower edge of the slot may preferably be provided with notches, in which the transverse pin 12 can be held fast when adjusted. 75 The support 7 which is only of small dimensions therefore also transmits no heat to the rod 9 and through the latter to the container 1 so that volatilization of the fuel is accordingly obviated.

80 Any other suitable gear known in this class of lamps for the purpose of lowering or raising the said support 7 may be employed.

The support 7 widens out conically upwards and has a suitable fastening device for 85 the base part 4 of the closely woven incandescent mantle 3. Since the gas evolved need only flow in contact with the mantle 3 externally, the latter may be more compactly woven and therefore stronger. The shape 90 to be given to the mantle corresponds to the shape of the flame.

95 As Figure 11 shows, the lower end of the rod 9 may be constructed as a rack 9^a, with which there meshes a gear 35 mounted on a spindle 34 provided with a handle.

The bearings or supports 10 and 11 are resiliently constructed so that they are only held in their position in the tube 5 by frictional pressure. They can therefore be subsequently inserted in the tube 5 of any finished lamp. Since they are perforated they do not prevent the passage of air, and are therefore constantly cooled, and transmit no heat to the fuel container and its contents. 100 The plate 7, which is only of small dimensions, therefore also transmits no heat to the rod 9, and through the latter to the said supports; any heating of the container and volatilization of the fuel is accordingly obviated. 105

110 The wick 6 and its outer carrier 15 can be raised and lowered by means of known toothed gearing, and a spindle 17. The tube 15 is guided in the tube 16, which is connected with a gallery carrying a lamp glass 24, and screwed into the aperture in the cover of the container 1.

115 In the case of lamps of known construction the adjustment of the flame and the regulation of the inner air supply is effected simultaneously with the raising and lowering of the wick. This adjustment is not an accurate one because the generation of gas increases when the wick is raised and at the same time the quantity of air supplied is reduced. When the wick is lowered the contrary occurs.

120 The main feature of the present invention consists in the fact that after adjustment of 130

the correct height of wick which is most favourable to the evolution of gas, the most favourable combustion proportions can be ensured independently of this adjustment of the wick. The supply of additional air to the flame from outside does not supplement merely the quantity of air necessary for complete combustion, but also exerts a regulating action upon the draught of the lamp, and alters the velocity of the draft and the cooling, in which case the angle at which the air meets the flame can be altered, for the purpose of altering the shape, and the dimensions of the flame and its capacity to exert lighting or heating effects.

For the production of these effects there serves according to the invention a fixing plate 21.

For explaining the principle of the invention, the fixing plate 21 has the shape of a flat ring surrounding that part of the wick 6 which projects out of the top of the wick guide 5, 5 below the margin of the wick. This ring which is preferably provided with some holes for permitting the passage of the outer cooling air is passed over the wick and arranged horizontally or nearly so and adjustable in relation to the height of the projecting part of the wick and is held by friction on the outer surface of the wick. The fixing plate, brought in its suitable position, divides the projecting part of the wick in a portion upwards the ring for the formation of the flame and in a cool portion below the ring towards the wick guide. The ring takes up the heat of the flame and prevents the striking back of the flame, burning on the margin of the wick, towards the part of wick below the ring.

In the preferred form of the fixing plate according to Fig. 1 this plate is constructed as a flat ring 21 with an elevated inner margin formed like a cap, which is loosely set upon the upper edge or margin of the wick 6 and is provided in the part of the cap, which rests upon the margin of the wick with holes 21^a suitably arranged for the formation of the designed shape of flame.

This fixing plate is loosely set up on the upper edge of the wick tube 16 when the wick 6 is screwed down into the wick guide 5, 16.

The fixing disc 21 shown in Fig. 2 is provided with a bent inner marginal part or rim 21^b. An air sleeve 23 with holes for leading the inner air flow to the flame burning at the holes 21^a of the cap like uppermost part of the fixing plate is inserted in the wick tube 5 or guide and can be shifted more or less in this latter. The fixing plate 21 carries on its outwardly extending part a flat ring 25 of wire gauze or perforated sheet iron, which ring 25 may be loosely set up or also in one piece with the fixing plate. The ring 25 aids in leading away the heat produced by the flame for strengthening the

cooling effect of the fixing plate. For the purpose of extinguishing the flame the wick is slowly turned down, the marginal part 21^b of the fixing plate being let down on the guide tube 5 and the margin of the wick passes out of contact with the perforated part of the fixing plate, so that the flame must extinguish.

The ring 25 serves also for cooling the flame, so that the latter cannot ignite the free part of the wick located below the fixing plate, if it should strike back owing to any sudden change in the air pressure, as for example in the event of a gust of wind blowing through the lamp glass from above.

In the constructional form according to Figs. 3 and 4 the wick 6 which is flat and guided in a tube 15 of rectangular cross section carries a modified form of fixing plate 21 of corresponding shape, the fixing plate resting loosely on the wick.

The ignition is effected in the manner previously described. The gas formed passes out through the holes 21^a of the fixing plate and burns. After ignition the free surface of the wick located below the fixing plate is lowered into the tube 15 to extinguish the flame below the fixing plate and is then raised to the position of most favorable gas generation.

Figs. 5 and 6 show a constructional form of the fixing plate for flat wicks, which has only two holes 21^a and is combined with a hollow ring 30 mounted thereon, which covers these holes 21^a, so that the gases evolved pass from these holes 21^a into the interior of the ring 30, which has in its upper wall apertures 30^a, at which the escaping gases are ignited. In this manner by the aid of a flat wick, a round flame can be produced. If desired, holes 30^b may likewise be provided at the inner and outer side walls of the ring 30.

The constructional form according to Figs. 7 and 8 likewise serves for the production of a round flame on a flat wick, and also for ensuring the internal air guidance. Upon the fixing plate 21 fitted to the wick is arranged inside the hollow ring 30 an air sleeve 23, which is exchangeable. At the side of the hollow ring is fitted a flat sieve ring 25 for the purpose previously indicated.

What I claim is:—

1. An appliance constructed as a lamp or stove for the complete combustion of liquid fuels for lighting and heating purposes, comprising a guide adapted to hold a wick projecting out of the top of said guide, a fixing plate having the shape of a flat ring, surrounding the projecting part of the wick below the margin of the wick and arranged horizontally or nearly so and adjustably in relation to the height of this projecting part of wick, this fixing plate dividing the latter in a portion upwards the ring for the formation of the flame and in a cool portion below the

ring towards the wick guide, and preventing the striking back of the flame to this lower part of wick, and means for guiding air along this latter part of the wick for the purpose of cooling it.

2. An appliance constructed as a lamp or stove for the complete combustion of liquid fuels for lighting and heating purposes, comprising a guide adapted to hold a wick projecting out of the top of said guide, a fixing plate having the shape of a flat ring surrounding the projecting part of the wick, with a cap like inner margin covering the upper margin of the wick and being adapted to rest loosely upon the wick, this cap shaped part being formed with holes in its top surface at which holes the flame burns, and means for guiding air along the part of the wick located below said fixing plate and projecting out of the wick guide for the purpose of cooling said part of the wick.

3. An appliance constructed as a lamp or stove for the complete combustion of liquid fuels for lighting and heating purposes, comprising a guide adapted to hold a wick projecting out of the top of said guide, a fixing plate having the shape of a flat ring surrounding the projecting part of the wick with a cap-like inner part covering the upper margin of the wick and being adapted to rest loosely upon the wick, this cap-shaped part being formed with holes in its top surface at which holes the flame burns and having an overhanging rim for covering the inner side of a round wick to a given distance from the margin of the wick towards the end of the wick guide, and means for guiding air along the part of the wick located below said fixing plate and projecting out of the wick guide for the purpose of cooling said part of the wick.

4. An appliance constructed as a lamp or stove for the complete combustion of liquid fuels for lighting and heating purposes, comprising a guide adapted to hold a wick projecting out of the top of said guide, a fixing plate having the shape of a flat ring surrounding the projecting part of the wick with a cap-like inner margin or part covering the upper margin of the wick, being adapted to rest loosely upon the wick and having holes in its top surface at which holes the flame burns, a flat perforated or sieve-like part carried by the fixing plate and projecting the outer-contour-line of this plate for aiding in preventing the striking back of the flame to the wick below the fixing plate and for reinforcing the cooling effect of the fixing plate, and means for guiding air along the part of the wick located below said fixing plate and projecting out of the wick guide for the purpose of cooling said part of the wick.

5. An appliance constructed as a lamp or stove for the complete combustion of liquid fuels for lighting and heating purposes, com-

prising a guide adapted to hold a wick projecting out of the top of said guide, a fixing plate having the shape of a flat ring surrounding the projecting part of the wick with a cap-like inner part covering the upper margin of the wick, being adapted to rest loosely upon the wick and having holes in its top surface at which holes the flame burns, means for guiding air along the part of the wick located below said fixing plate and projecting out of the wick tube for the purpose of cooling the said part of the wick, and an air sleeve formed with perforations for the escape of air supplied internally to the flame through the wick guide in the case of round wick burners.

6. An appliance constructed as a lamp or stove for the complete combustion of liquid fuels for lighting and heating purposes, comprising a guide adapted to hold a wick projecting out of the top of said guide, a fixing plate having the shape of a flat ring surrounding the projecting part of the wick with a cap like inner part or margin covering the upper margin of the wick, being adapted to rest loosely upon the wick and having holes in its top surface at which holes the flame burns, means for guiding air along the part of the wick located below said fixing plate and projecting out of the wick guide for the purpose of cooling the said part of the wick, and an air sleeve formed with perforations for the escape of air supplied internally to the flame through the wick guide in the case of round wick burners, said air sleeve being adapted to pass through a central aperture and slide adjustably into the wick guide.

7. An appliance constructed as a lamp or stove for the complete combustion of liquid fuels for lighting and heating purposes, comprising a guide adapted to hold a wick projecting out of the top of said guide, a fixing plate having the shape of a flat rectangular ring surrounding the projecting part of the wick with a cap-like part covering the upper margin of the wick, being adapted to rest loosely upon the wick, in combination with a hollow annular portion mounted upon the upper side of the cap-like rectangular part, both parts being in communication by holes in the top surface of the cap-like part and the annular portion having holes in its surface at which the flame burns.

8. An appliance constructed as a lamp or stove for the complete combustion of liquid fuels for lighting and heating purposes, comprising a guide adapted to hold a wick projecting out of the top of said guide, a fixing plate having the shape of a flat ring surrounding the projecting part of the wick with a cap-like inner margin covering the upper margin of the wick, being adapted to rest loosely upon the wick and having holes in its top surface at which holes the flame burns,

means for guiding air along the part of the wick located below said fixing plate and projecting out of the wick guide for the purpose of cooling the said part of the wick, an adjustable support for a closed meshed incandescent mantle mounted thereon above the fixing plate and having a shape which adapts it to the shape of the flame burning on the surface of the cap-like part of the fixing plate, the flame enveloping the mantle on its outside only.

In testimony whereof I affix my signature.

ALADÁR DOMAN.
